UNITED STATES PATENT OFFICE

2,530,755

APPARATUS FOR FILLING CONTAINERS
WITH LIQUIDDavid William Bingham, Brighton, Victoria,
AustraliaApplication September 23, 1946, Serial No. 698,684
In Australia January 16, 1946

7 Claims. (Cl. 226—95)

1

This invention relates to apparatus for filling bottles and other containers with predetermined quantities of liquid and the like and more particularly concerns apparatus of the type which employs a vacuum pump or the like for withdrawing air from the bottle to be filled to thereby cause the liquid to flow into the bottle under the influence of atmospheric pressure.

The primary object of the present invention is to provide improved apparatus of the kind indicated for filling a wide variety of bottles and other containers of many different shapes and sizes while they are being carried forward on a conveyor and without interrupting such forward movement.

Another object is to provide, in apparatus of the kind indicated, an improved filling head which is adapted automatically to move the container into the correct filling position and then fill it whereupon the liquid supply is automatically cut off and undesirable dripping of the liquid is either eliminated or reduced to a minimum.

Other objects and various constructional features of the invention will be more readily apparent from the following description of one practical embodiment.

Referring to the drawings which form part of this specification:

Fig. 1 is a front elevation of apparatus for filling bottles and other containers with liquid in accordance with one embodiment of the invention, parts being omitted for convenience of illustration.

Figs. 2 and 3 are an end view and a plan view respectively of the parts seen in Fig. 1.

Fig. 4 is a side view, on an enlarged scale, showing portion of a filling head conveyor and ramps associated therewith.

Figs. 5 and 6 are a plan view and a sectional elevation respectively of the parts seen in Fig. 4.

Fig. 7 is a sectional elevation on an enlarged scale of one of the filling heads.

Fig. 8 is a sectional elevation taken approximately on the line VIII—VIII of Fig. 7.

Fig. 9 is a fragmentary sectional elevation on an enlarged scale of a common distributor valve.

Fig. 10 is a sectional plan taken approximately on the line X—X of Fig. 9.

Fig. 11 is a sectional elevation taken approximately on the line XI—XI of Fig. 9.

The improved apparatus includes a supporting frame 2 having an endless conveyor 3 for the bottles or other containers to be filled. This

2

bottle conveyor preferably moves forward in a straight line path.

Mounted upon the frame is a bulk storage tank 6 for the liquid, the tank being provided with a feed pipe 7 connected to a common distributor valve 8 having a plurality of flexible discharge pipes 9 leading to a series of filling heads 11 hereinafter described.

The apparatus also includes a vacuum pump 12 and an associated tank 13, a separator device 14 for separating any liquid that may enter the vacuum pipe system 16 and means for conveying a plurality of the feeding heads lengthwise of the bottle conveyor 3 and at the same speed.

15 The apparatus also preferably includes a power unit such as an electric motor 17 for operating the various movable parts thereof.

The series of filling heads may be carried by an endless chain conveyor 21, as best shown in Figs. 2-6, portion of which is located above the bottle conveyor 3 so as to extend lengthwise thereof in substantially parallel relationship. The endless chain conveyor passes around driving sprockets 22 carried by upright shafts 23. Associated with the chain conveyor is a trackway 24 adapted to be slidably engaged by shoulders 26 on the chain links so as to prevent vertical displacement of the conveyor. The latter may also be provided with rollers 27 adapted to engage the trackway for preventing lateral displacement of the conveyor.

The aforesaid filling heads 11 are mounted upon the chain conveyor in longitudinally spaced relationship. The support for each filling head may consist of an upright plate 28 connected to the chain conveyor 21 and provided with a dovetail or like guideway 29 for a vertical slide member 31 to which the filling head is connected. The slide member may be provided with a roller 32 adapted to engage ramps 33 which are located above the chain conveyor and adapted to automatically raise and lower the filling heads in relation to the bottle conveyor. Instead of the ramp and roller arrangement, any other suitable means may be employed for automatically effecting such vertical movements of the filling heads as they are carried forward by their conveyor.

The aforesaid filling heads constitute an important feature of this invention. Each filling head 11, as best shown in Figs. 5-8 may comprise a body portion 36 which is bolted as at 37 or secured in any other suitable manner to its slide member 31. The body portion is provided with an inlet port 38 for removable connection to

one of the liquid discharge pipes 9, the inlet port being in communication with an internal transfer passage 39 leading to a liquid discharge nozzle 41 which is spring influenced and vertically slidable. The discharge nozzle is slidably accommodated within an open ended hole 42 which extends in a substantially vertical direction between the transfer passage 39 and the bottom of the body portion so as to form a vertical guideway for the discharge nozzle. A rolling sealing ring 43 or any other suitable type of seal is provided for preventing the escape of liquid through the guideway during the vertical sliding movements of the discharge nozzle.

The body portion is also provided with a vacuum pipe 46 which may extend from the top of the body portion across the internal transfer passage 39 and downwardly through the discharge nozzle 41, the external diameter of the vacuum pipe being smaller than the internal diameter of the nozzle so as to provide an annular passage 47 for the discharge of liquid through the nozzle when so desired. The vacuum pipe may be provided with a series of radial vanes 48 for centralizing it within the nozzle whilst the lower end of the pipe may be provided with an enlarged head 49 on which an annular stepped shoulder 51 may be formed to provide a seating adapted to be engaged by the lower end of the nozzle. The vacuum pipe 46 and the liquid inlet port 38 may both be fitted with nipples and screw couplings for detachable connection to their respective pipe lines.

Mounted upon and secured to the discharge nozzle 41 beneath the body portion 36 is a hollow centering member 52 for the bottles or other containers. The centering member may include inner and outer sections 53 and 54 respectively adapted to be screwed together. The outer section may be provided with a stepped shoulder 56 so that it may clamp a resilient sealing ring 57 in position against a similar shoulder on the inner section and the discharge nozzle.

The lower end portion of said outer section 54 is preferably of flared bell mouthed formation and provided with an inclined circumferential passage 58 adapted to direct the mouth of a bottle or the like 4 (Fig. 7) on to the aforesaid sealing ring 57.

The hollow centering member 52 and the body portion 36 are relatively movable and for this purpose may be connected together by a plurality of parallel pins or studs 61 anchored to the body portion and passing freely through apertured arms 62 outstanding from the hollow centering member. Coiled springs 63 preferably encircle the connecting studs for the purpose of normally forcing the centering member 52 downwardly and thus carrying the lower end of the nozzle 41 into engagement with its seating 56 on the vacuum pipe.

The aforesaid common distributor valve 8, as best shown in Figs. 9-11 includes a stationary member 66 and a rotary member 67, the stationary member having a common outlet port 68 for the liquid and also a common vacuum exhaust port 69, the two common ports being adapted to register successively with a plurality of pairs of circumferentially spaced liquid and vacuum ports 71 and 72 respectively in the rotary valve member each of which is connected by the flexible tubing 9 to one of the filling heads 11.

The axis of the distributor valve is preferably substantially vertical, the rotary member 67 being carried by an upstanding power driven ro-

tatable post 73 while the stationary valve member 66 is secured to an overhanging stationary torque arm 74 anchored at its opposite end to any convenient part of the machine frame.

5 The aforesaid common liquid and vacuum ports 68 and 69 in the stationary valve member 66 communicate through internal passages 76 with screw couplings or the like 77, one of which is adapted for removable connection to the main 10 feed pipe 7 leading from the liquid storage tank 6 while the other is connected to the pipe line 16 leading to the vacuum tank 13.

The stationary and rotatable members 66 and 67 of the distributor valve may be of complementary tapered formation so as to form a suitable rotary seal therebetween. The parts may be resiliently connected together by means of connecting bolts 81 carried by the rotary member 67 and passing freely through apertures in a rotatable bearing ring 82 mounted on an annular shoulder 83 on the stationary valve member 66, the outer end portions of the connecting bolts being fitted with lock nuts and coiled springs 84 or the like located between the lock 25 nuts and the adjacent face of the bearing ring.

In order to accommodate different sized bottles the improved apparatus may include any suitable type of elevating mechanism whereby relative movement may be effected between the 30 bottle conveyor 3 and the filling heads 11 and parts associated therewith, in accordance with requirements.

In use bottles or other containers to be filled are placed in suitable seatings 87 on the bottle 35 conveyor 3 in advance of the filling heads 11 which are adapted to move lengthwise of the bottle conveyor above the container and at the same forward speed.

As an empty bottle and a filling head approach 40 each other the filling head roller 32 engages one of the ramps 33 and thus causes the head to be automatically moved downwardly until the bell mouthed centering member 52 engages the top of the bottle and, if necessary, tilts it slightly so 45 as to bring the mouth of the bottle into engagement with the sealing ring 57, the liquid discharge nozzle 41 and the vacuum pipe 46 being positioned within the top of the bottle neck. Engagement of the bottle with the sealing ring 57 arrests the downward movement of the discharge nozzle with the result that the vacuum pipe continues to move downwardly and thus opens the lower end of the discharge nozzle. At this stage 50 in the forward movement of the bottle the liquid and vacuum ports 71, 72 of the respective filling head, on the distributor valve 8 are brought into 55 registry with the common liquid and vacuum ports 68, 69 therein, whereby air is withdrawn from the bottle and liquid from the main storage tank 6 is induced to flow into the container under the influence of atmospheric pressure.

The period during which the filling head 11 is open while in contact with the bottle is such that a predetermined quantity of liquid is permitted to enter the container sufficient to fill it whereupon the filling head roller 32 engages another ramp 33 and is automatically lifted out of contact with the container, thus automatically cutting off the supply of liquid, the ports 71, 72 being also moved out of registry with the common ports 68, 69 in the distributor valve.

It will be appreciated from the foregoing that the filling of the containers takes place automatically as they are moving forward in a straight

line on their conveyor and without any interruption of such forward movement.

If for any reason more than the predetermined quantity of liquid enters a container, the excess liquid is drawn off through the vacuum pipe and separated and returned to the main storage tank 6 by the aforesaid separating device 14.

It is to be understood that various modifications, alterations, and/or additions may be incorporated in the foregoing construction and arrangement of parts without departing from the ambit of the invention as defined by the appended claims.

Having now described my invention, what I claim as new and desire to secure by Letters Patent is:

1. Apparatus for filling bottles and other containers with predetermined quantities of liquid and the like, an endless conveyor for a series of filling heads, said conveyor having a trackway for guiding the filling heads forward in a straight line above and in parallel spaced relationship with a separate conveyor for bottles to be filled, means for effecting vertical movement of each filling head relative to its conveyor as it passes through said trackway, and means for preventing both vertical and lateral displacement of the filling head conveyor while it is passing through said trackway.

2. Apparatus according to claim 1 wherein said means for preventing displacement of the filling head conveyor comprises shoulders on said conveyor adapted to slide lengthwise on complementary shoulders on said trackway and rollers carried by said filling head conveyor for engaging spaced frame members on said trackway.

3. Apparatus according to claim 1 in combination with ramp means located above and in parallel spaced relationship with said bottle conveyor and adapted to engage movable supports on said filling head conveyor for each said filling head whereby the latter are caused to move downwardly as they engage said ramp means and are returned to their original position when leaving the ramp means.

4. Apparatus for filling bottles and other containers with predetermined quantities of liquid, comprising a supporting frame, an endless bottle conveyor thereon and having a straight line forward path, a liquid storage tank, a vacuum pump, a common distributor valve connected to said storage tank and said vacuum pump and comprising stationary and rotary valve members, the latter being carried by an upright power driven rotatable post while the former is carried by an overhanging torque arm fixed at its opposite end to said frame, a plurality of filling heads carried by an endless conveyor having a portion located above and in parallel spaced relationship with said bottle conveyor, each filling head being connected by piping to said common distributing valve and having a liquid discharge nozzle and a vacuum pipe located within said nozzle and forming an annular liquid passage therebetween, an annular seating on the lower end of said vacuum pipe for engaging the lower end of said nozzle which carries a hollow centering member for directing the neck of a bottle to be filled over the lower ends of said nozzle and vacuum pipe and on to a sealing ring within said centering member, and means for lowering and raising each said filler head in relation to bottle conveyor as it passes thereover and moves forward at the same speed.

5. Apparatus for filling bottles and other containers with predetermined quantities of liquid, comprising a supporting frame, an endless bottle conveyor thereon and having a straight line forward path, a liquid storage tank, a vacuum pump, a common distributor valve connected to said storage tank and said vacuum pump and comprising of interfitting stationary and rotary valve members resiliently connected together, said rotary valve member being carried by an upright power driven rotatable post while the former is carried by an overhanging torque arm fixed at its opposite end to said frame, a plurality of filling heads carried by an endless conveyor having a portion located above and in parallel spaced relationship with said bottle conveyor, each filling head being connected by piping to said common distributing valve and having a liquid discharge nozzle and a vacuum pipe located within said nozzle and forming an annular liquid passage therebetween, an annular seating on the lower end of said vacuum pipe for engaging the lower end of said nozzle which carries a hollow centering member resiliently connected to a body portion of said filling head for directing the neck of a bottle to be filled over the lower ends of said nozzle and vacuum pipe and on to a sealing ring within said centering member, means for lowering and raising each filler head in relation to its conveyor as the latter moves forward over its straight line path, and elevating mechanism for effecting relative movement between the bottle conveyor and the filler heads and parts associated therewith.

35. 6. Apparatus for filling bottles and other containers with predetermined quantities of liquid and the like, comprising in combination a supporting frame, an endless bottle conveyor thereon and having a straight line forward path, a liquid storage tank on said frame, a vacuum pump on said frame, a series of filling heads, each including a liquid discharge nozzle and a vacuum pipe and a hollow centering member for inserting said nozzle and pipe into the neck of a bottle and directing the mouth of the bottle onto a sealing member which is displaceable for opening said liquid discharge nozzle, a second conveyor for said filling heads and having a straight line portion mounted above and in parallel spaced relationship to said bottle conveyor, a common distributor valve connected by piping to said liquid storage tank and said vacuum pump and also to each of said filling heads, said distributor valve including interfitting stationary and rotary valve members having a common liquid outlet port and a common vacuum exhaust port in said stationary valve member and a series of circumferentially spaced pairs of liquid and vacuum ports in said rotary valve member which is carried by an upright power driven rotatable post while the stationary valve member is carried by an overhanging torque arm anchored at its opposite end to said frame, means for lowering and raising each of said filling heads in relation to the bottle conveyor as said filling heads move forward in parallel spaced relationship with said bottle conveyor and at the same forward speed, and means for driving said conveyors, filling heads and distributor valve in synchronization.

7. Apparatus according to claim 6 wherein said common liquid and vacuum ports in the stationary valve member communicate through internal passages with exterior couplings adapted for connection to a main liquid feed pipe leading to

7
said storage tank and to a pipe leading to said vacuum pump, said stationary and rotatable valve members being of complementary tapered formation so as to form a rotary seal therebetween, and also being connected together by means of a bearing ring which is carried by a seating on the stationary valve member and is resiliently connected to said rotary valve member.
